UNITED STATES PATENT OFFICE

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

DISAPPEARING MACHINE REST

Application filed October 5, 1929. Serial No. 397,519.

This invention relates to sewing machine tables, more particularly of the drop-head type having a plural-sectioned flush cover for closing the opening in the table-top through which the sewing machine is dropped when not in use. In the manufacture of tables of this type it is customary to make the table-top and cover-sections from the same piece of wood to maintain uniformity of color and continuity of the graining; the piece which is sawed from the table-top in cutting the aperture therein being used for the cover which, in turn, is sawed into a plurality of sections subsequently hinged together, so that the section or sections of the cover not used when the sewing machine is raised to operative position may be swung to a concealed position below the table-top.

It is customary to use one of the cover-sections to support one edge of the sewing machine bed when the sewing machine is raised to operative position and, for this purpose, the practice was to rabbet or undercut the edge of the machine-bed supporting section and glue a strip of wood in the cut-out portion; the glued-in strip projecting beyond the edge of the cover-section to form a machine-bed supporting ledge. The adjacent cover-section was rabbeted to receive such ledge when the sections of the cover were swung to lie in a common plane. These wood-working operations were troublesome and costly.

In my Patent No. 1,745,781; issued Feb. 4, 1930, there is disclosed a drop-head sewing machine table having a foldable cover, the machine-bed-supporting section of which is provided with one or more disappearing machine rests in the form of metal slides received in suitable guideways screwed to the cover-section. The rests are backed by springs which project them beyond the edge of the cover-section to machine-supporting position when the adjacent cover-section is swung to concealed position.

It has been found in some cases that because of the vibration of the sewing machine head there is a tendency for the rests to creep back into their recesses in the supporting

cover-section and allow the sewing machine to drop into the cavity of the table.

It is an object of the present invention to provide locking means which will effectively prevent displacement of the rest from machine-supporting position while they are supporting the machine.

Another object of the invention is to so devise the locking means that no special attention need be given thereto by the operator in raising the sewing machine to operative position or lowering it to inoperative position.

According to the present improvement, in its preferred embodiment, a slight amount of vertical play is provided for between the rests and their guideways. The proximate surfaces of the rests and guideways which support the weight of the sewing machine are provided with interengaging projections and depressions which lock the rests against endwise movement while they are subjected to the weight of the sewing machine. When the sewing machine is purposely lowered into the cavity of the table and the concealed cover-section is swung upwardly to initial position, its edge engages the rests and first lifts them sufficiently to disengage the projections from the depressions, subsequently pushing the rests back of the edge and into the recesses of their supporting cover-section.

In the accompanying drawings, Fig. 1 is a top plan view of a sewing machine table embodying the invention. Fig. 2 is a transverse vertical section through the table with the sewing machine head in concealed position. Fig. 3 is a similar view with the sewing machine head raised to operative position. Fig. 4 is an edge view of the cover-section which carries the machine-bed supporting rests. Fig. 5 is a detail sectional view through two adjoining cover-sections showing the machine-bed supported by one of the machine-bed rests. Fig. 6 is a similar view showing the foldable cover-section in the act of lifting the rest preparatory to pushing it to concealed position. Fig. 7 is a disassembled perspective view of the machine-bed rest shown in Figs. 5 and 6 and

Fig. 8 is an enlarged sectional view of the locking projection on the rest-guideway.

In the preferred embodiment of the invention illustrated, 1 represents the top of a sewing machine table having an aperture 2 to the edge 3 of which is connected by hinges 4 the bed 5 of the sewing machine 6 which may be swung about the hinges 4 to raise and lower it through the aperture 3 between the concealed position shown in Fig. 2 and the operative position shown in Fig. 3.

When the sewing machine 6 is in lowered position, the aperture 2 is closed by a flush cover comprising three sections 7^a, 7^b and 7^c; 15 the sections 7^a and 7^b being connected together by the hinges 8 and the sections 7^b and 7^c being connected by the hinges 9. The cover, as a whole, is connected by hinges 10 to the edge of the aperture 3 opposite the edge to which the sewing machine hinges 4 are secured. The cover-sections 7^a, 7^b, 7^c are sawed from the same piece of wood which is cut out of the table-top 1 in sawing the aperture 3, thus maintaining uniformity of 20 color and continuity of the graining of the exposed wood surface.

Let into recesses 11 in the edge of the cover-section 7^a adjoining the section 7^b are a pair of disappearing machine-bed rests 12 in the form of Z-shaped elements, the lower horizontal bars 13 of which are slidably mounted in ways formed by the superposed flat and troughed plates, 14 and 15, respectively. A stop-pin 16 carried by the bar 13 of each rest 12 enters a slot 17 in its supporting troughed plate 15 and limits the sliding movement of the rest. An expansion spring 18 in each recess 11 bears against the upper end of the inclined bar 19, Fig. 5, of each rest and yieldingly urges the rest to move outwardly from its recess 11 across the edge of its supporting cover-section 7^a to machine-bed supporting position, Fig. 3, in which position the cover-sections 7^b and 7^c are 45 swung under the section 7^a to a concealed position below the top 1.

The bottom face of the slide-bar 13 of each rest 12 is formed with a transverse depression or groove 20 which, when the rest is projected to machine-supporting position, Fig. 5, is engaged by the transverse projection 21 struck up from the forward edge of the plate 15, thus locking the rest in its machine-supporting position. It will be observed that it is the proximate surfaces 22, 23 of the rest 13 and guideway-plate 15 which are pressed together by the weight of the sewing machine and which are provided with the depression 20 and projection 21. 55 Thus the rest is held locked to the plate 15 by the weight of the sewing machine.

When the sewing machine is lowered through the aperture 2 its weight is necessarily removed from the rests 12. During 60 the swinging movement of the cover-section

7^b from concealed position, Fig. 5 to a position in a plane with the cover-section 7^a, the wear-plates 24 on the edge of the cover-section 7^b moving in circular arcs about the hinge-pins 8, engage the rests 12 with an upward followed by an inward motion and lift the rests clear of the projections 21, subsequently pushing the rests into the recesses 11. 70

An additional groove 20' may be provided alongside the groove 20 to be engaged by the projection 21 if, for any reason, such projection fails to engage the groove 20. 75

While I have shown and described one embodiment of the invention, it is to be understood that the invention is susceptible of embodiment in various other forms, as will readily occur to those skilled in the art. 80

Having thus set forth the nature of the invention, what I claim herein is:— 85

1. A sewing machine table having a top formed with an aperture and means for supporting a sewing machine in operative position in said aperture, said means including a rest having a movement in a direction substantially parallel to the plane of the table-top from non-supporting to machine-supporting position, and rest-locking means in engagement with which said rest is maintained by the weight of the supported sewing machine, said rest and rest-locking means having an interlocking projection and depression. 90

2. A sewing machine table having a top formed with an aperture and means for supporting a sewing machine in operative position in said aperture, said means including a rest having a movement in a direction substantially parallel to the plane of the table-top from non-supporting to machine-supporting position, and stationary rest-locking means into engagement with which said rest is moved transversely of the plane of the table-top. 100

3. In a sewing machine table, the combination with a plurality of cover-sections having their abutting edges hinged together, of a spring-pressed sewing machine bed-support let into one of said edges and engaging the other edge under spring-pressure and automatically projectable from said one of said edges when the cover-sections are relatively swung about their hinge-connection, and automatically operative means for locking said bed-support in its projected position. 110

4. A sewing machine table having a top formed with an aperture and a cavity below said top into which the sewing machine is dropped through said aperture when not in use, a flush cover adapted to close said aperture and comprising a plurality of sections hinged together and to said top, a guideway carried by one of said cover-sections adjacent the adjoining cover-section, a machine-bed support movable longitudinally and lat- 120 125 130

- erally of said guideway, said rest and guideway having in their proximate surfaces which are held pressed together by the weight of the supported sewing machine interlocking projection and depression means, and a spring for projecting said rest into machine-supporting position when said cover-sections are swung out of a common plane about their hinge-connection.
- 5 5. A sewing machine table having a top formed with a sewing machine bed-receiving aperture and with a cavity below said aperture into which the sewing machine may be dropped through said aperture when not in use, a cover hinged to said top and adapted to close said aperture, a movably mounted machine-bed rest engaging said cover when the latter is in closed position, a spring acting to move said rest from inoperative to machine-supporting position when said cover is opened to expose said aperture, and automatically interlocking projection and depression means for locking said rest in machine-supporting position.
- 10 6. In a sewing machine table, a pair of relatively movable sections hinged together and having meeting edges, a guideway on one of said sections, a machine-bed rest disposed in said guideway, said rest and guideway having interlocking projection and depression means, said rest being movable longitudinally of said guideway across the edge of its supporting section between its inoperative and operative positions and laterally of said guideway for engagement and disengagement of said interlocking means, a spring for projecting said rest to operative position when said sections are relatively moved about their hinge connection, the initial engagement of said rest and one of said sections, when said sections are relatively moved to restore their edges in meeting relation, effecting a lateral movement of said rest in said guideway to unlock said rest, followed by a longitudinal movement of said rest in said guideway to inoperative position.
- 15 40 45

In testimony whereof, I have signed my name to this specification.

50
